FREDERICK HENRY ROYCE, OF ELMSTEAD, WEST WITTERING, CHICHESTER, ENGLAND,
ASSIGNOR TO ROLLS ROYCE LIMITED, OF DERBY, ENGLAND

CARBURETOR

Application filed January 16, 1929, Serial No. 332,969, and in Great Britain January 24, 1928.

This invention has reference to carburetors for internal combustion engines, in connection with which the power output of the engine is frequently varying as in the case of a motor car engine. It relates to the type generally known as "expanding carburetors", that is to say, in which the air way past the orifice or orifices from which the petrol issues into the mixing chamber and the metering 5 constriction or jet are automatically varied 10 in cross section area to meet the changing conditions.

In all such carburetors the objects aimed at are that the speed of travel of the air past the fuel orifice or orifices should be as far 15 as possible constant to ensure a constant atomization of the petrol or other liquid fuel and that the ratio of petrol, or other liquid fuel, to air should as far as possible, be constant.

20 It is also desirable that the tendency of the atomized liquid to condense and/or be deposited between the mixing chamber and the cylinder should be reduced to a minimum.

The main object of this invention is to attain 25 these ends better than has been done in carburetors heretofore in use. The invention has the further objects of enabling a carburetor of the type to be constructed with a straight through gas passage, of reducing 30 friction of moving parts to a minimum, and reducing the possibility of particles of dust interfering with the working of the carburetor.

35 For the purpose of securing the best atomization of gasoline throughout the air supply I arrange several features in combination, namely, that the main air supply shall pass through the throat and not as in many carburetors be admitted beyond the throat, and 40 thirdly that before issuing from such orifice the gasoline shall have been atomized by means of an air-bleed device.

45 For the purpose of preventing deposit of gasoline during the passage of the fuel mixture from the throat to the induction pipe I not only secure the best general atomization and diffusion of the gasoline throughout the air supply by means aforesaid, but in addition 50 arrange the mechanical parts so that there

need be no obstruction in the passage from the throat to the throttle valve.

In the accompanying drawings is illustrated an example of apparatus made in accordance with this invention.

55 Fig. 1 is a sectional elevation taken on a very irregular line in order to show several parts which are really in different planes. Fig. 2 is a part sectional plan view taken on the line Z—Z of Fig. 1. Fig. 3 is a part section on line 3—3 of Fig. 2. Fig. 4 is a part section on line 4—4 of Fig. 2. Fig. 5 is a part section on line 5—5 of Fig. 2, Figs. 3, 4 and 5 being drawn to an enlarged scale and Fig. 6 is a section through Fig. 5 on the 60 line 6—6.

65 a is the main casting constituting the main body of the carburetor comprising the air inlet a¹, two coaxial circular orifices a² and a³ to form and accommodate the throat, an inclined tunnel a⁴ extending from the lower part of the air inlet to the top of the casting to accommodate an air bleed suction device, a part a⁵ forming a cylindrical cavity for the reception of the metering device, the float 70 tank a⁶ of quasi horse shoe shape (embracing the upper half of the air inlet, the orifice a², the inclined tunnel, the metering device hereinafter described, and a tube containing a connecting rod hereinafter described) and an 75 extension a⁷ having a flat upper surface and with an opening to the air a⁸ to support other parts hereinafter referred to. a⁹ is a hole connecting the said tunnel and said cavity. The 80 fixed member of the throat is formed in two 85 parts, to wit, by the curved walls of the orifice a², and the tubular part b which is threaded and screwed into the casting a. b¹ is a tubular member secured by bolts (not shown) to the casting a, b² the throttle valve 85 and b³ the induction pipe provided with a heating jacket. c is the moving member of the throat. c¹ a sleeve threaded for part of its length and screwed into the member c, 90 supporting a divided annular member c², and 95 telescopically slideable over the upstanding sleeve c³ of the member c⁴, which is seated in the orifice a³ in the casting a, and held in position by means of the member c⁵ which rests, on one side, on a shoulder formed on the 100

casting α and, on the other side, is secured by means of shank c^7 pivotally hinged on the casting α , and formed with a thread, engaging a slot in the member c^6 , and having the butterfly nut c^8 screened thereon. d and d^1 are two floats in the float tank attached to a spindle d^2 provided with projecting jaws d^3 which engage the valve needle d^4 . e is a tubular member, the lower part of which is of irregular cross section shape as shown in Figure 2, and the upper part of which is a cylindrical shape, being e^1 of Fig. 1, mounted on the part a^7 of the casting α , and formed with a downward projecting cylindrical part e^2 which fits into a hole in the part a^7 . e^3 is a piston slideable in the cylindrical part e^1 with a downward projecting cylindrical part e^4 which slideably fits for part of its length in, and is guided by the cylindrical projection e^2 . e^5 is a diaphragm across the piston e^3 . e^6 are a row of holes through the wall of the said piston. e^7 is a cover enclosing with an air tight joint the upper end of the cylindrical part e^1 . e^8 is a member to secure the cover e^7 held in position on one side by the shoulder e^9 and on the other side by a rod e^{10} , swinging on a pivot e^{11} , and engaging a slot e^{12} formed in the member e^8 , and the butterfly nut e^{13} . e^{14} is a spring reacting between cover e^7 and diaphragm e^5 . The member e is secured to part a^7 by set screws e^{15} (see Fig. 2). f are a number of holes through the fixed member of the choke communicating with an annular space f^1 which is in communication 35 with the interior of the cylindrical part e^1 via the conduits f^2 and f^3 . g is a rod pivotally hinged at the upper end to the cylindrical projection e^4 , and at the lower end to one arm of the lever g^1 , rocking on a fulcrum g^2 between and supported by two ears g^6 (one only shown) on the casting α , the other end of which lever is pivotally hinged at g^3 to a rod g^4 which is connected by a ball and socket joint g^5 to the moving member c of the choke. 40

The diffuser now to be described is contained in the tunnel α^4 of the casting α . h is a plug with a cylindrical part h^1 externally threaded engaging a tapped thread in the tunnel α^4 , h^2 and h^3 are tubes within the tunnel α^4 and co-axial therewith, forming the annular spaces or conduits h^4 and h^5 , the space h^4 terminating at the upper end against the part h^1 and the space h^5 being in free communication at its upper end with the inside of the tube h^3 which is in free communication at its lower end with the air, h^6 are rows of holes through the wall of the tube h^2 , h^7 an annular space around the tube h^2 , h^8 a conduit, h^9 an annular space in the fixed member of the throat, and h^{10} a row of holes leading to the mixing chamber. 50

The metering device is constructed as follows:—

i is a tubular member having a narrow diameter part i^1 which fits into the cavity in

part a^6 of the casting α , and an enlarged part i^2 externally threaded to engage a thread tapped in the casting α , and having a row of holes i^3 through its wall. i^4 is a valve needle tapered at its lower end, and at its upper end shaped to receive the cylindrical end i^5 of a lever i^6 hereinafter described. The lever i^6 rocks on a pivot i^7 projected eccentrically from a shaft i^8 (see Figs. 5 and 6) and is actuated by a push rod i^9 extending through a tube i^{10} passing through holes in the casting α and expanding at each end to make a tight fit therein. The push rod at its lower end is a loose fit in a hollow plug i^{11} , inserted in tube i^{10} and is provided with a flat terminal which rests on a roller i^{12} rotating on a pivot projected from the lever g^1 and at its upper end is provided with a spherical end i^{14} which engages a spherical socket i^{15} in the lever i^6 . 85

The hand control is illustrated in Figures 5 and 6.

j is a hollow bracket, having a part j^1 cut away to receive the end of the lever j^6 , secured to casting α by stud j^3 and located by dowel pin j^4 and with a hole j^5 therethrough tangential to, but with half its diameter within, the bore of the bracket. The shaft j^8 has an annular groove corresponding to the hole j^5 , and when assembled in the bracket is secured by a screw j^6 , j^7 is a lever secured to the shaft and actuatable by the driver. 90

Referring to Fig. 4, k is a bracket secured by set screw k^1 to the casting α and located by dowel pin k^2 , k^3 is a coil spring reacting on the needle of the metering valve against the reaction of the lever i^6 . 100

The functioning of the carburetor is as follows:— 105

Gasoline from the float tank passes through holes i^3 of the metering device, thence through the hole a^9 to the air bleed suction device entering the annular space h^4 and flowing through the holes h^6 fills (to the gasoline level in the tank) the annular space h^5 . When the engine is running the gasoline in the spaces h^4 and h^5 (atomized by air passing up the tube h^3 down the space h^5 and through holes h^6) passes into the annular space h^7 and via the conduit h^8 annular space h^9 and holes h^{10} to the mixing chamber. 110

The vacuum in the mixing chamber is communicated to the cylindrical part e^1 by way of the passages f^2 , f^3 , whereupon the piston e^3 is lifted against the reaction of spring e^{14} and through the medium of the lever g^1 and rod g^4 the moving member of the throat c is drawn down, and through the medium of the rod i^9 and the lever i^6 the needle i^4 is lifted thus allowing a greater quantity of air and gasoline to be supplied to the engine. 120

The arrangement of the vacuum cylinder e^1 and the piston therein is such that there 130

is no sudden movement. The space between the piston and the bottom part of the cylinder e^1 is not directly vented, and until air has passed through holes e^6 and leaked through the clearance between the cylinder wall and the piston, the movement of the piston is delayed.

When the hand control is exercised the fulcrum i^7 is raised or lowered thereby lowering or raising the sphere end of the lever i^8 and with it the needle of the metering valve.

The construction enables a straight and unobstructed passage from the throat to the throttle to be provided thus reducing unintentional throttling of the mixture supply, and secures in a new and improved manner a constant speed of air past the gasoline issuing orifices, with a resulting predetermined proportion of air and gasoline, and a varying supply of gasoline and air to meet varying conditions of engine speed and throttle opening, and further a hand control which while altering the proportion of gasoline to air does not disturb the required varying of supply. Further the friction of moving parts is reduced to a minimum.

What I claim is:—

1. A carburetor for an internal combustion engine comprising a throat consisting of an annular fixed member and a movable member of circular cross section adapted to move co-axially towards or away from such annular member, a mixing chamber, a variable metering jet, an air bleed suction device arranged and adapted to vaporize the liquid fuel between the metering and mixing chambers and means independent of the pressure of air on the movable member for automatically adjusting the members of the throat relatively and the variable metering jet both consistently with the vacuum in the mixing chamber.

2. A carburetor for an internal combustion engine comprising a throat consisting of an annular fixed member and a movable member of circular cross section adapted to move co-axially towards or away from such annular member, one air way and that through the throat, a mixing chamber, a variable metering jet, an air bleed suction device arranged and adapted to vaporize the liquid fuel between the metering and mixing chambers and means independent of the pressure of air on the movable member for automatically adjusting the members of the throat relatively and the variable metering jet both consistently with the vacuum in the mixing chamber.

3. A carburetor for an internal combustion engine comprising a throat consisting of an annular fixed member and a movable member of circular cross section adapted to be moved co-axially towards or away from such annular member, a throttle valve, a mixing chamber consisting of a cylindrical passage

axial with the throat and unobstructed except for the throttle valve, a variable metering jet, an air bleed suction device arranged and adapted to vaporize the liquid fuel between the metering and mixing chambers and means independent of the pressure of air on the movable member for automatically adjusting the members of the throat relatively and the variable metering jet consistently with the vacuum in the mixing chamber.

4. A carburetor for internal combustion engines comprising an airway, a throat consisting of an annular venturi projecting from the wall of the air-way and a streamlined movable member adapted to be moved co-axially towards or away from such annular member, a mixing chamber, a variable metering jet, an air bleed suction device arranged and adapted to vaporize the liquid fuel between the metering and mixing chambers and means independent of the pressure of air on the movable member for automatically adjusting the members of the throat relatively and the variable metering jet consistently with the vacuum in the mixing chamber.

5. A carburetor as claimed in claim 4, having a number of gasoline orifices issuing from the side of the annular venturi at the highest point of such venturi.

6. A carburetor for internal combustion engines comprising a throat consisting of an annular fixed member and a movable member of circular cross section adapted to be moved co-axially towards or away from such annular member, a float tank, a variable metering jet, consisting of a pipe through which the gasoline passes in its passage from the float tank and a taper ended rod slidable in such pipe to obstruct, as required, the passage way therethrough, an air bleed suction device arranged and adapted to vaporize the liquid fuel between the metering and mixing chambers and means, independent of the pressure of air on the movable member, for automatically adjusting the members of the throat relatively and the variable metering jet, consistently with the vacuum in the mixing chamber.

7. A carburetor for an internal combustion engine comprising a throat consisting of an annular fixed member and a movable member of circular cross section adapted to be moved co-axially towards or away from such annular member, a variable metering jet, an air bleed suction device arranged and adapted to vaporize the liquid fuel between the metering and mixing chambers, consisting of a central and two co-axial, spaced apart, upstanding pipes, the intermediate pipe having a number of circumferential rows of holes therethrough, the central pipe being open at the lower end to the air, the central and intermediate pipe being in free communication, but otherwise enclosed at

the upper end, the spaces between the central and intermediate and the intermediate and outer pipes being closed at the lower end, the outer pipe being at its upper end in direct communication with the issuing orifices, and means, independent of the pressure of air on the movable member, for automatically adjusting the members of the throat relatively, and the metering jet consistently with the 10 vacuum in the mixing chamber.

8. A carburetor for an internal combustion engine comprising a throat consisting of an annular fixed member and a movable member of circular cross section adapted to move co-axially towards or away from such annular member, a mixing chamber, a variable metering jet, an air bleed suction device arranged and adapted to vaporize the liquid fuel between the metering and mixing 15 chambers, and means, independent of the pressure of air on the movable member, for automatically adjusting the members of the throat relatively and the variable metering jet consistently with the vacuum in the mixing chamber, the means for actuating the moving throat member, consisting of a piston in a closed chamber one side of which is in communication with the mixing chamber, and the other side, by restricted air leaks, 20 open to the air, a lever rocking on a fulcrum intermediate its ends, one end begin operatively connected to the piston and the other end operably connected to the moving member of the throat, and the means for actuating 25 the metering valve consisting of another lever pivotally fulcrumed at one end, its free end actuating the said valve against the reaction of a spring and a push rod engaged by the first said lever and actuating the second said lever.

9. A carburetor as claimed in claim 8, with a hand operated control varying the ratio of, but not the automatic variability of the gasoline supply.

10. A carburetor as claimed in claim number 8, with a hand operated control varying the ratio of, but not the automatic variability, comprising a shaft on which the lever actuating the metering valve is mounted eccentrically and a lever projecting from such shaft operable by the driver.

11. A carburetor for an internal combustion engine comprising an airway, a throat consisting of an annular venturi projected 55 from the wall of the airway and a movable member of circular cross section adapted to be moved co-axially towards or away from such annular member, a mixing chamber, a variable metering jet, an air bleed suction 60 device arranged and adapted to vaporize the liquid fuel between the metering and mixing chambers and means independent of the pressure of air on the movable member for automatically adjusting the members of 65 the throat relatively and the variable meter-

ing jet consistently with the vacuum in the mixing chamber, a number of gasoline orifices issuing from the venturi in the plane of its highest point, the means for actuating the moving throat member consisting of a 70 piston in a closed chamber, a circumferential row of holes issuing from the Venturi member of the throat in substantially the same plane as the gasoline issuing orifices communicating with one side of the said piston, a series of restricted air leaks communicating with the other side of the said piston, a lever rocking on a fulcrum intermediate its ends, one end being operatively connected to the piston and the other end operably connected to the moving member of the throat, and the means for actuating the metering valve consisting of another lever pivotally fulcrumed at one end, its free 75 end actuating the said valve against the reaction of a spring and a push rod engaged by the said lever and actuating the second said lever.

In testimony whereof I have hereunto affixed my signature.

FREDERICK HENRY ROYCE.
